(57) **CLAIM**

The ornamental design for a motorcycle bracket for mounting license plates and turn signal lights, as shown and described.

DESCRIPTION

FIG. 1 is a front right perspective view of a novel motorcycle bracket for mounting license plates and turn signal lights, with a top bent mounting plate and bottom plate for mounting a license plate and rectangular flanges for mounting turn signal lights.

FIG. 2 is a rear view of the design of FIG. 1.

FIG. 3 is a right side view of the design of FIG. 1.

FIG. 4 is a right side view of the design of FIG. 2.

FIG. 5 is a front view of the design of FIG. 1 shown in upright condition; and,

FIG. 6 is a rear view of the design of FIG. 2 shown in upright condition.
